UNITED STATES PATENT OFFICE.

JOHN E. HANIFEN, OF PHILADELPHIA, PENNSYLVANIA.

DESIGN FOR ORNAMENTAL STOCKING FABRIC.

SPECIFICATION forming part of Design No. 11,753, dated April 27, 1880.

Application filed November 29, 1879. Term of patent 3½ years.

To all whom it may concern:

Be it known that I, JOHN E. HANIFEN, of the city and county of Philadelphia, and State of Pennsylvania, have originated and designed an Ornamental Stocking Fabric, of which the following is a full, clear, and exact description, reference being had to the accompanying photographic illustration, making part of this specification.

- 10 The background *a* of the fabric is formed of plain stitches, on which appear tuck-stitches *b*, separated from each other and forming straight broken lines, which are arranged in alternating lighter and darker stripes of about
- 15 equal width. The only variation from straightness of line is caused by the necessary curvature of the stocking.

I am aware that the design patent of Delahey, No. 3,062, dated June 2, 1868, shows a fabric having stitches arranged in broken lines on a background, forming stripes. I do not claim said design.

What I claim is—

The design for ornamental stocking fabric, consisting of the background *a* of plain stitches and the straight broken lines of tuck-stitches *b*, arranged in alternating lighter and darker stripes of about equal width, substantially as described and shown.

JOHN E. HANIFEN.
